United States Patent Office.

JONATHAN G. EVANS, OF ALBANY, NEW YORK,

Design No. 2,814, dated October 22, 1867.

DESIGN FOR A MODEL OF THE ANCIENT CITY OF JERUSALEM.

The Schedule referred to in these Letters Patent and making part of the same.

Be it known that I, JONATHAN G. EVANS, of the city of Albany, State of New York, have produced a new and original Design, being a Model, in relief-plan, of the Ancient City of Jerusalem; and I declare the accompanying delineation (photograph) to be a full and complete representation of the said model.

What I claim, and desire to secure by Letters Patent, is—
The design as shown and described.

Witnesses:

RICHD. VARICK DE WITT,
DUPLEY W. DE WITT.

JONATHAN G. EVANS.
